UNITED STATES PATENT OFFICE.

EDWARD N. KRONINGER AND DANIEL B. KRONINGER, OF ALLEN TOWN, PENNSYLVANIA.

PLANT FOR HEATING GREENHOUSES.

SPECIFICATION forming part of Letters Patent No. 564,756, dated July 28, 1896.

Application filed October 3, 1895. Serial No. 564,539. (No model.)

To all whom it may concern:

Be it known that we, EDWARD N. KRONINGER and DANIEL B. KRONINGER, citizens of the United States, residing at Allentown, 5 in the county of Lehigh and State of Pennsylvania, have invented a new and useful Plant for Heating Greenhouses, of which the following is a specification.

This invention relates to heating apparatus 10 designed most especially for tempering the atmosphere of greenhouses, and with slight modifications can be adapted for dwellings, buildings, and other structures, and has for its object to utilize and distribute the heat to 15 the best possible advantage and prevent any wasting thereof, thereby economizing in the consumption of fuel and avoiding the necessity for forcing the furnace under normal conditions.

20 The plant or heating system embodies in its organization a bank of heating-pipes subdivided into sections, distributing or radiating pipes connected with the respective sections of heating-pipes, return-pipes likewise 25 in communication with the said sections of heating-pipes and forming in effect a continuation of the heat distributing or radiating pipes, an expansion-chamber connected with the heat distributing or radiating pipes and 30 with the return-pipes, manifolds intermediate of the expansion-chamber and the pipes connected therewith, a feed-pipe, and a manifold connecting the feed-pipe with the respective return-pipes, the parts being 35 arranged and operating substantially in the manner as will more fully appear hereinafter.

The many objects and advantages resultant 40 from the peculiar construction of the plant will appear as the nature of the invention is better understood, and to this end the improvement consists, essentially, of the novel features of construction and combinations of parts, substantially as herein illustrated, described, and most especially noted in the 45 claims.

In the accompanying drawings is illustrated 50 an embodiment of the invention, although slight changes in the details and arrangement may be made without departing from the spirit of the invention, and in said drawings—

Figure 1 is a longitudinal section showing the invention applied to a greenhouse. Fig. 2 is a transverse section of the boiler about on the line X X of Fig. 1, on a larger scale. 55 Fig. 3 is a detail perspective view showing the manifold having the feed-pipe connected therewith, and which is in communication with the return-pipes. Fig. 4 is a detail perspective view showing the manifolds, which 60 are in communication with the expansion-chamber and with the heat distributing and return pipes.

The same reference-numerals denote like and corresponding parts in all the figures of 65 the drawings, and in the latter 1 indicates a greenhouse of ordinary construction, showing the plant or system applied thereto, and 2 is the boiler, conveniently located and preferably disposed in a pit, so as to be out of the 70 way.

The boiler comprises a bank of heating-pipes, which are arranged in groups or sections 75 3, and which are inclosed by masonry in the usual manner, the latter being formed at one end with a fire-box 4 and an ash-pit 5 in any desired manner to attain the end, which is to thoroughly and effectually heat the aforesaid bank of pipes. There will be as many groups or sections 3 as desired and 80 according to the capacity and size of the boiler, and each group or section will comprise a series of pipes which are disposed in parallelism and which are connected in pairs at opposite ends by return-bends common in 85 the art of constructing radiators. In order to attain the best possible results, the groups or sections of heating-pipes are disposed in parallelism and in a progressive series reckoning from a horizontal plane, the middle 90 groups or sections being the highest and the outer groups or sections the lowest, and the positions of the intermediate groups or sections gradually falling away from the middle point toward the sides, as shown most clearly 95 in Fig. 2. The upper and the lower heating-pipes of each group or section are extended and connect, respectively, with a distributing or radiating pipe 6 and a return-pipe 7.

The heat distributing or radiating pipes 6 100 extend within the greenhouse either above, below, or to one side of the benches, or may

occupy any desired position, so as to distribute the heat to the best advantage. A manifold 8 is connected with each distributing or radiating pipe 6 by means of small pipes 9, 5 each being provided with a valve 10, so as to disconnect any one of the pipes 6 from the manifold in the event of the said pipe leaking or requiring to be repaired. This manifold 8 is connected by means of a pipe 11 10 with an expansion-chamber 12, located at the highest point of the system, and which contains a supply of water to prevent the exhausting of the pipes 6, and this expansion-chamber is supplied with a safety-valve 13 to relieve the plant of any abnormal pressure.

The return-pipes 7, one being provided for each distributing or radiating pipe 6, are connected with the latter and are located in a relatively lower plane, and are designed to 20 return the water to the boiler, to be again heated and circulated through the system of pipes. The several pipes 6 and 7 slant toward the boiler, so as to secure the best possible results and insure a thorough and positive 25 circulation of the water. A manifold 14, similar in construction to the manifold 8, is connected by a pipe 15 with the expansion-chamber 12 and by small pipes 16 with the several return-pipes 7, each of the small pipes 30 16 having a valve 17 to admit of any pipe 7 being cut off from the manifold for purposes of repair or when desired.

A manifold 18 has the feed-pipe 19 connected therewith and has communication 35 with the respective return-pipes 7 by small pipes 20, which latter are supplied with valves 21 to admit of any return-pipe being cut off from the manifold 18 for any desired purpose. The feed-pipe 19 communicates with any suitable 40 source of water supply, and has a valve 22 to cut off the supply after the plant or system receives a proper supply of water for the effective and efficient operation of the apparatus.

45 The operation of the plant is as follows: The several pipes and manifolds being supplied with water and the expansion-chamber 12 being properly filled, and all the valves except 22 being open, and the fire being started 50 in the fire-box, the water in the groups or sections of heating-pipes 3 will be heated and will flow to the distributing or radiating pipes 6, and the cool water from the return-pipes 7 will flow into the heating-pipes and in turn 55 be heated, thereby establishing a circulation of water which will be continued so long as the fire is maintained in the fire-box and so long as the plant is in working operation. The chamber 12 allows for the expansion of 60 the water incident to the heating thereof, and also contains a sufficient quantity of water to maintain the pipes in prime condition for performing efficient work.

65 The arrangement of the pipes 6 and 7 is immaterial to the successful operation of the invention and will depend largely upon the nature of the work and the caprice of the manu-

facturer, but in the disposition of the pipes it is essential that the return-pipes occupy a relatively lower plane than the heat distributing or radiating pipes with which they are connected, thereby insuring a circulation of the water. It is also imperative that the expansion-chamber be located above the top-most distributing or radiating pipe, so as to 70 maintain the pipes in normal condition and prevent the water receding therefrom. The boiler may be located within or exterior to the greenhouse, as may be found most convenient, and one boiler may be arranged to heat 75 one or a series of greenhouses, as may be required.

When the boiler is of considerable length, pillars 23 will be provided to support the bank of heating-pipes, and these pillars have steps 85 24, upon which rest the sections or groups of pipes. The pipes of each group or section are held in vertical relation by means of inverted U-bands 23, having their side members secured together by bolts 26, the lower 90 ends of the bands resting upon the steps 24. The arch 27 is near the topmost heating-pipes to retain the heat in close contact therewith. By this arrangement of the parts the heat is utilized to the best advantage. Hence less coal 95 is required to heat a given space as compared with heaters of ordinary construction. The furnace will need cleaning from time to time, and to enable access being had thereto doors 100 28 are provided in the side of the masonry between the pillars 23. These doors may be formed in any of the usual ways. In case the pipes are differently located in the greenhouse, so that it is not practical to employ a manifold for connecting the radiating and return pipes, the latter may be connected in any 105 convenient and approved manner to secure the desired end.

Having thus described the invention, what is claimed as new is—

1. In a system or plant for heating greenhouses or other structures, the combination of a boiler comprising a sectional bank of heating-pipes, a series of heat distributing or radiating pipes having individual connection 115 with the respective boiler-sections, a corresponding series of return-pipes having connection at their rear ends with the respective heat-distributing pipes and with the aforesaid corresponding boiler-sections, an elevated expansion-chamber, a manifold having connection with the rear ends of the heat-distributing pipes and with the expansion-chamber, and a second manifold arranged in a lower plane than the first-mentioned manifold and 120 having connection with the expansion-chamber and with the receiving ends of the return-pipes, substantially as shown for the purpose 125 described.

2. The herein shown and described plant 130 for heating greenhouses and other structures, comprising a boiler, a sectional bank of heating-pipes disposed within the boiler in a progressive declining series from a middle

point, a series of heat distributing or radiating pipes having individual connection with the respective boiler-sections, a corresponding series of return-pipes having connection 5 at their rear ends with the respective heat-distributing pipes and with the boiler-sections, a manifold 18 having valved connection with the return-pipes near their front ends, a feed-pipe having communication with the 10 said manifold, an elevated expansion-chamber, a manifold 8 having valved connection with the rear ends of the respective heat-distributing pipes and with the expansion-cham- ber, and a manifold 14 having valved connection with the rear ends of the return-pipes 15 and with the said expansion-chamber, substantially as shown for the purpose set forth.

In testimony that we claim the foregoing as our own we have hereto affixed our signatures in the presence of two witnesses.

EDWARD N. KRONINGER.
DANIEL B. KRONINGER.
